ADJUSTABLE GARMENT HANGER

Thomas A. Bell, Ridgefield Park, N. J.

Application July 13, 1950, Serial No. 173,593

1 Claim. (Cl. 223—89)

1

The present invention relates to a garment hanger and refers more particularly to the type of hanger comprising means for adjusting the effective length of the portions of the hanger engaging the shoulders of the garment.

A disadvantage of such type of hangers has been that their fairly complicated structure has entailed comparatively high manufacturing cost so that the article could not compete economically with the very cheap nonadjustable hanger.

A further disadvantage has been that the slideable construction usually employed to impart adjustability has yielded a wobbly product lacking in convenience of operation.

An object of the present invention is the provision of an adjustable hanger very cheap to manufacture.

Another object is that the hanger shall be made of materials familiar to the manufacturers of the commoner nonadjustable hangers and which can be made with very little change in manufacturing machinery.

Still another object is that the hanger shall have a sure and pleasant "feel" during operation, particularly during adjustment.

Other objects will appear as the description proceeds.

In accomplishing the objects of the present invention the hanger is provided with a central tubular section comprising downwardly sloping shoulder portions and extension members slidably mounted therein. The extension members are constituted by a single length of wire and comprise two parallel legs and a foot extending inwardly from one leg toward the other. The tube is stamped or otherwise constricted at its end to constitute two tubes snugly engaging the two legs, and the foot acts as a stop which when it engages the throat between the two tubes prevents withdrawal of the extension from the main tube. The double telescopic engagement of the legs in the tubes provides pleasantly smooth operation at low cost.

Other objects of this invention will in part be obvious and in part hereinafter be pointed out. The invention accordingly consists in the features of construction, combinations of elements and arrangements of parts which will be exemplified in the constructions hereinafter described. In the accompanying drawing in which is shown one of the various possible illustrative embodiments of this invention:

Figure 1 is a front view of the hanger, showing an extended position thereof in broken lines.

Figure 2 is a fragmentary plan view thereof.

2

Figure 3 is a plan view of an extension member.

Figure 4 is a section on the line 4—4 of Figure 2.

Figure 5 is a section on the line 5—5 of Figure 2.

Referring now in detail to the drawings, the improved hanger 10 comprises the body portion 11 which is a tube of circular cross section bent to comprise a central portion 12 and downwardly and outwardly sloping shoulder portions 13, 14 which engage the inner surfaces of the shoulders of the garment.

The support engaging means comprise the hook 15 for engaging a bar or other support, the yoke 16 preferably integral therewith as illustrated, and the loops 17 extending integrally from the yoke 16 and encompassing portion 12 so the yoke and hook are revoluble about the axis of portion 12 and the hook may therefore be folded inwardly for compactness when the hanger 10 is packed into a suitcase.

The extension members 18, 19 are preferably constituted of a single length of metal wire as illustrated in Figure 3, and comprise a comparatively wide loop portion 20, leg portions 21, 22 extending substantially parallel one with the other, and the foot portion 23 extending laterally inward from leg 22 towards leg 21.

The outer ends of shoulder portions 13, 14 are stamped or constricted in any other desired manner so as to form the double tubular portion 24 comprising the substantially cylindrical tubes 25, 26 side by side and integral with the portions 13, 14. The legs 21, 22 slide snugly in the tubes 25, 26 and the throat 27 between tubes 25, 26 prevents complete withdrawal of the extension members 18, 19 from tubes 13, 14 by blocking engagement with the foot portions 23.

The snug engagement of tubes 25, 26 around substantially the entire circumference of each of the legs 21, 22 keeps the loops 20 in a plane parallel to the plane drawn through the axes of the tubes 25, 26 and also provides very smooth sliding motion of the members 20 in the shoulder portions 13, 14.

Because the portions of extension members 18, 19 within the shoulder portions 13, 14 are totally enclosed, it is impossible to pinch one's fingers while using the hanger, a marked advantage over adjustable hangers now available.

As the body portion 11 is formed by merely bending and stamping a cylindrical tube of light metal, such as aluminum, it enjoys the advantage of economy of manufacture over types in which a flat sheet is flanged in order to obtain only partial enclosure of the extension members.

In such case the above mentioned possibility still remains of pinching the fingers between the parts of the device which define the limit of sliding motion by coming into abutment.

A cross bar 28 may be provided, comprising the tube 29 stamped down around or otherwise constrictively encompassing the wire loop 30, as at 31, loop 30 being wrapped around loop 20. The extension member 32 is a wire slidable in tube 29 and comprising the loop 33 wrapped around the second loop 20.

It will thus be seen that there is provided a device in which the several objects of this invention are achieved, and which is well adapted to meet the conditions of practical use. As various possible embodiments might be made of the above invention, and as various changes might be made in the embodiments above set forth, it is to be understood that all matter herein set forth or shown in the accompanying drawing is to be interpreted as illustrative and not in a limiting sense.

What is claimed is:

In a garment hanger, the combination of a tubular shoulder engaging portion and an extension member slidably engaged therein for varying the effective length thereof, said extension mem-

ber being constituted by a single length of metal wire and comprising a loop portion, said extension member further comprising leg portions and a member extending inwardly from one of said leg portions toward said other leg portion, said tubular portion being substantially cylindrical and constricted at its outer end to constitute a substantially double cylindrical portion comprising two tubes side by side and a throat portion located between said tubes, one of said legs being slidably located in each of said two tubes and snugly engaged thereby substantially around the entire circumference of said leg, and said inwardly extending member being blockingly engaged by said throat portion at the outer limit of its travel to prevent complete withdrawal of said extension member from said first mentioned tubular portion.
